UNITED STATES PATENT OFFICE.

CHARLES N. SOWDEN, OF GUANTÁNAMO, CUBA.

BOTTLE-HOLDER.

1,079,192.

Specification of Letters Patent.

Patented Nov. 18, 1913.

Application filed February 26, 1913. Serial No. 750,798.

To all whom it may concern:

Be it known that I, CHARLES N. SOWDEN, a British subject, at present residing at Guantánamo, Santiago de Cuba Province, 5 Cuba, have invented a new and Improved Bottle-Holder, of which the following is a full, clear, and exact description.

My invention is designed more particularly to provide a bottle holder for use on 10 automobiles and other vehicles, for holding thermos bottles.

It is a design of my invention to provide a holder for the indicated purpose, which may be employed to properly hold and sustain the bottle in position, and which will 15 at the same time permit of the ready removal of the bottle when desired.

A further design of the invention is to provide a holder in which the elements are 20 foldable into a small compass when not required to hold a bottle.

The invention will be particularly explained in the specific description herein-after to be given.

Reference is to be had to the accompanying drawings forming a part of this specification, in which similar characters of reference indicate corresponding parts in all the views.

Figure 1 is a sectional side elevation of 30 my improved holder in use; Fig. 2 is a similar view with the bottle-engaging elements in folded position; and Fig. 3 is a front view of the device with the parts in the 35 folded position.

In constructing the device in accordance with my invention, a body or back 10 is provided, designed to be applied in upright position and affixed as by screws 11 or their 40 equivalent, to a convenient point on the body of a vehicle, such as an automobile, or to other support. The body 10 may be in the form of a flat plate, as shown. To the lower end of the body 10 is pivoted a rest 45 12, on which a thermos bottle 13 may be seated. For lightness, the rest 12 may be in the form of a ring, as shown, the ring being of cross sectional shape to approximately conform to the rounded lower edge 50 of the bottle, and at the same time to be reasonably ornamental; in the instance shown the ring is concavo-convex in cross section. On the inner side of the ring is an annular cushion 15, of rubber or equivalent 55 soft material.

The pivoting of the seat 12 is effected by

a transverse pin 16, which passes through a radial extension 12^a on the ring, and through spaced lugs 17 which project forwardly from the face of the body 10, at the lower end thereof. The extension 12^a is square on two sides so that there is an end face 18 and a top face 19 at right angles to each other adjacent to the pivot 16, either of which faces brings up against the free end 60 of a plate spring 20, which is secured to the face of the body 10 by a rivet 21, or equivalent means. When the seat 12 is in a horizontal position to receive a bottle, as indicated in Fig. 1, the face 18 will be 65 pressed against by the spring 20, so that the spring resists the turning movement of the rest on its pivot pin 16. The rest 12, however, may be swung upwardly on its pivot and fold parallel with the face of the body 70 75 10, or approximately so, as shown in Figs. 2 and 3, in which position the spring will bear against the face 19. To afford clearance for the spring 20 when flexed by the swinging of the rest 12 from one position 80 to another, an opening 22 is produced in the body 10 at the back of the spring, the upper wall of the opening inclining downwardly and rearwardly, as shown in Figs. 1 and 2.

At the upper end of the body 10 a retainer for the bottle is provided, and like the rest 12 is in the form of a ring 24. The ring is flaring to conform approximately to the rounded upper end 13^a of the bottle, 90 and is lined interiorly with a cushion 25 of rubber or other soft material. The retaining ring 24 is pivoted by a pin 26 that passes through a lug 27 on the retainer and through spaced lugs 28 formed at the upper end of the body 10. Flat faces 29, 30, are formed on the retainer at the lug 27, against which a plate spring 31 may bear, the spring being secured by rivets 32 or otherwise to the upper end of the body, at 100 the front thereof, and the body is formed with an opening 33 similar to the opening 23, to afford clearance for the spring and permit it to flex when the retainer 24 is swung on its pivot pin 26.

The bottle and the retainer 24 may be manipulated in the entering of the bottle to the upright position shown in full lines in Fig. 1, for the removal of the bottle. One position of the bottle is indicated in dotted lines, 110 showing said bottle and the retainer 24 tilted at an angle. It will be observed that

the face 30 on the retainer 24 is not parallel with the spring 31 when the retainer is in a horizontal position engaging the bottle. The result is that the spring will press against 5 the ring at a single point 34, or at least press against a small surface of the retainer above the pivot pin 26, and will thus exert its pressure through a short lever arm, and rock the retainer downwardly so as to cause the 10 retainer to exert a downward pressure on the bottle, pressing the latter firmly into the seat 12. The action of the upper spring 31 on the retainer 24, it will be observed, is somewhat different from the action of the 15 spring 20 on the ring seat 12, since with the latter, the spring, by pressing against the face 18 at a point adjacent to the pivot 16 and above the latter, will rock the ring only to the horizontal position, with the lower 20 end of the face 18 pressed firmly against the face of the body 10, and the ring seat will thus be arrested in its downward movement by the face of the body 10, while the retainer 24 has a downward movement limited by 25 the bottle. The retainer 24 may be folded to the position shown in Figs. 2 and 3, approximately parallel with the body 10 and in line with the folded ring seat 12, so that both

the seat and the ring are out of the way when not required to hold the bottle.

Having thus described my invention, I claim as new, and desire to secure by Letters Patent:

In a bottle holder, a seat for a bottle, a retainer to receive and engage the bottle at a point distant from the seat, said retainer being mounted to swing to an outer position to engage the bottle, or to a folded position at approximately right angles to the first position, and a spring adjacent to the pivot 35 of the retainer and exerting pressure against the latter, the retainer having at an end thereof a surface opposed to the spring, and engaging the latter at a point at one side of the pivot, said point of engagement between 40 the spring and the retainer resulting in the spring acting as a lever arm to press the retainer against the bottle.

In testimony whereof I have signed my name to this specification in the presence of 50 two subscribing witnesses.

CHARLES N. SOWDEN.
